(57) **CLAIM**

We claim the ornamental design for an athletic helmet, as shown and described.

DESCRIPTION

FIG. 1 is an isometric view of an athletic helmet.

FIG. 2 is a front view of an athletic helmet.

FIG. 3 is a rear view of an athletic helmet.

FIG. 4 is a left view of an athletic helmet.

FIG. 5 is a right view of an athletic helmet.

FIG. 6 is a top view of an athletic helmet; and,

FIG. 7 is a bottom view of an athletic helmet.

The environmental structure shown in broken lines forms no part of the claimed design.
